ROLLER PAINTER

Alva L. Kitselman, II, Palo Alto, Calif.

Application May 5, 1936, Serial No. 78,064

11 Claims.

(Cl. 91—49)

This invention relates to roller painters, and more particularly to a device intended for use in marking traffic lines on highways.

An important object of the invention is to provide a simple and relatively inexpensive device by means of which lines may be quickly and easily applied to highways or any other desired surfaces.

A further object is to provide a device of the character referred to wherein a roller is employed for applying paint to the desired surface and wherein novel means is employed for supporting the roller and for supplying paint thereto.

A further object is to provide novel means for controlling the flow of paint from the roller.

A further object is to provide a novel form of fabric applicator covering the roller to insure a uniform distribution of paint.

A further object is to provide a roller having spaced openings for the flow of paint therethrough and provided with an absorbent fabric covering to insure the distribution of paint throughout the periphery of the roller and thus insure the uniform application of paint on the desired surface.

A further object is to provide a roller painter of the character referred to wherein the roller is readily demountable to permit the use of different rollers for any purpose, as where painted lines of different widths are desired.

A further object is to provide a painting device of the character referred to having means for supporting the roller with respect to the supply tank, and to provide means for supplying paint to the interior of the roller axially thereof.

A further object is to provide common means for supporting the roller for rotation about its axis and for supplying paint or other surface coating composition to the interior of the roller.

Other objects and advantages of the invention will become apparent during the course of the following description.

In the drawings I have shown several embodiments of the invention. In this showing:

Figure 1 is a front elevation,

Figure 2 is an axial sectional view through the roller and associated parts,

Figure 3 is a section on line 3—3 of Figure 2,

Figure 4 is an elevation of a slightly modified form of apparatus, parts being broken away and parts being shown in section,

Figure 5 is a front elevation of a modified form of the invention,

Figure 6 is a sectional view taken axially through the roller and associated parts, and,

Figure 7 is a face view of a fabric distributor.

Referring to Figure 1, the numeral 10 designates a tank or reservoir for paint or other surface coating composition, and the tank is provided with upper and lower caps 11 and 12 respectively. The cap 12 may be rigidly fixed to the tank while the cap 11 is removable to permit the tank 10 to be filled and emptied. Any suitable means (not shown) may be provided for normally securing the cap 11 in position. Any desired handle means may be employed for facilitating the movement of the device, and for the purpose of illustration, the tank 10 has been shown as being provided with outstanding handles 13.

The cap 12 is provided with a plurality of studs 14 at one side thereof and a plurality of tubular nipples 15 at the opposite side. One of the nipples 15 is plugged as at 17, for a purpose to be described. As shown in Figure 1, the studs are solid and are secured against the solid adjacent wall portions of the cap 12 and selectively form supports for the painting roller to be described. The nipples 15 are tubular and communicate with the interior of the tank to feed paint to the roller in a manner to be described.

Referring to Figure 1 the numeral 18 designates a union by means of which an arm 19 is rigidly secured to one of the studs 14. The arm 19 may be tubular and is curved inwardly at its lower end as at 20. The lower end of the arm referred to is adapted to support a painting roller indicated as a whole by the numeral 21. The body of this roller is formed of a pair of 35 complementary sections 22 divided centrally of the width of the roller to permit them to be separated for a purpose to be described, the two sections being secured together by clamping bolts 23. One of the sections 22 carries a stub shaft 40 extending into the end 20 of the arm 19 and journaled with respect thereto by anti-friction bearings 25. The inner end of the arm 20 is provided with a flange 26 lying against the adjacent wall of the adjacent section 22 and fixed 45 against axial movement with respect thereto by a plate 27 secured in position by screws 28. The arm 19 forms the sole support for the roller, as will become apparent.

The other section 22 is connected to the means 50 for supplying paint or other surface coating composition to the interior of the rollers, such means including an elbow 29 secured in position in a manner to be described. A rubber or similar flexible tube 30 is connected at one end to the 55

elbow 29 and at the other end to a preferably metallic pipe 31. This pipe has its other end connected by a rubber or similar sleeve 32 to one of the nipples 15. Accordingly it will be apparent that the tank 10 communicates with the interior of the roller to supply paint thereto.

A valve device indicated as a whole by the numeral 33 is adapted to control the flow of paint outwardly from the roller through openings 34 formed in the adjacent edges of the section 22. The valve device comprises a disk like center portion 35 having a plurality of spokes or arms 36 extending outwardly therefrom and each carrying a valve 37 at its outer end conforming to the curvature of the inner peripheral portion of the roller and fitting snugly thereagainst. The valves 37 correspond in number and arrangement to the openings 34 and are movable to cover and uncover these openings upon actuation of a handle 38 projecting from one of the casing sections 22 through an arcuate slot 39 formed therein. It will be apparent that the disk portion of the valve covers the slot 39 and effectively prevents leakage therethrough.

The disk portion 35 of the valve lies against the wall of one of the sections 22, as shown in Figure 2, and common means may be employed for securing this disk and the elbow 29 in position. Referring to Figure 2, the numeral 40 designates a threaded sleeve having a flange 41 at its inner end seating on the inner face of the disk 35. A nut 43 is threaded on the outer end of the sleeve 40 and has a portion engaging a peripheral flange 44 formed on the elbow 29. It will be apparent that the outer end of the nut 43 seats against the flange 44 which, in turn, seats against the end of the sleeve 40, and accordingly the nut 43 and flange 41 effectually hold the parts together without creating any binding action between the disk 35 and the adjacent section 22.

An absorbent fabric covering 45 is arranged over the roller to distribute paint peripherally with respect thereto between the openings 34 to insure the uniform application of paint on the desired surface. The cover 45 carries an elastic band 46 at each edge thereof, and these bands contract against flanges 47 carried by the sections 22 to form a leak-proof joint and assist in excluding air from the interior of the roller.

The roller painter described is particularly intended for use in painting on horizontal surfaces and the slightly modified form of the invention shown in Figure 4 is applicable for painting on vertical surfaces under which conditions the tank 10 may be held horizontally or inclined downwardly away from the roller. With the form of the invention described, there would be an inadequate supply of paint to the roller. In the form of the invention shown in Figure 4 a piston 48 is reciprocable in the tank 10 and may be urged toward the roller end of the tank by means of fluid pressure delivered to the tank through a flexible hose 49 connected to a suitable source of fluid pressure.

In the form of the invention shown in Figures 5 and 6, common means is employed for rotatably supporting the roller and for supplying paint to the interior thereof. In such form of the invention a tank 50 may be employed which is generally similar to the tank 10 previously described, and the tank is preferably provided with a suitable form of handles 51. A removable top 52 held in position by any suitable means (not shown) may be removed to permit the tank to be filled. The lower end of the tank is provided

with an outlet tube 53 arranged in axial alignment with the tank. A plurality of other outlet tubes 54 may lead from the tank angularly with respect thereto as shown in Figures 5 and 6. Caps 55 are shown as closing the outlet tubes 54 which are not in use.

A roller similar to the roller previously described is employed and is indicated as a whole by the numeral 56. This roller has a metallic body portion made up of complementary sections 57 and 58 bolted together as at 59. These sections are very similar to the sections 22 previously described, but have been shown in the present instance as having groups of smaller outlet openings 60 for the passage of paint or other surface coating composition from the interior of the body. A valve disk 61 is rotatable against the side wall of the section 58 and is provided with valves 62 each adapted to control one of the groups of openings 60. An operating handle 63 extends through a slot 64 formed in the body member 58 and operates the valve disk 61 in the same manner that the handle 38 operates the valve 33.

A supporting pipe 65 is threaded on the outlet tube 53 as shown in Figure 6, but it will be apparent that this pipe may be threaded on one of the outlet tubes 54, in which case the cap 55 covering such tube will be threaded on the tube 53. The pipe 65 has its lower end turned inwardly as at 66 and terminates in an axial extension 67 through which paint flows from the pipe 65 into the interior of the roller. A nut 68 is threaded on the inner end of the extension 67 and retains the valve disk 61 in snug contact with the wall of the section 58.

The lower end of the pipe 65 is also provided with a portion 69 concentric with the extension 67, and anti-friction bearings 70 are arranged between the portion 69 of the pipe 65 and a circular flange 71 formed centrally of the adjacent wall of the section 58. The portion 69 of the supporting pipe is also provided with an outstanding flange 72 engaged by an annular plate 73 secured to the section 58 as at 74. The plate 73 acts as a thrust bearing in the same manner as the plate 21, shown in Figure 2.

An absorbent fabric covering 75 is arranged over the roller as shown in Figure 6. Whereas the fabric covering 45 previously described is provided with openings in opposite sides, it will be apparent that in the form of the invention shown in Figure 6, the single pipe 65 acts as both the support for the roller and the means for supplying paint thereto. Accordingly the cover 75 may be provided with only one opening 76 in one side thereof, and such opening is surrounded by an elastic band 77 to maintain the wall of the opening 76 in snug contact with a flange 78 carried by the section 58, thus assisting in excluding air from beneath the fabric cover. It will be apparent however, that one of the fabric covers 45 may be employed with the form of the invention shown in Figures 5 and 6 since there obviously is no objection to providing openings in both sides of the fabric cover.

The operation of the form of the invention shown in Figures 1, 2 and 3 is as follows:

The roller is effectively supported for rotation by the single arm 19, thus leaving the opposite side of the roller free to permit the supplying of surface coating composition to the interior of the roller. The sleeve 18 rigidly connects the arm 19 to the tank independently of the hose and pipe connections at the opposite side of the roller, and

the latter connections supply paint axially to the roller. The paint is supplied to the absorbent covering 49 which peripherally distributes the paint, and in operation, it merely is necessary for 5 the operator to grasp the handles 13 and push the device to roll the roller over the line which it is desired to paint. When the painting operation is completed, the valve device is closed by operating the handle 38. Under such conditions each valve 10 37 closes its associated opening 34. It will be noted that the clamping bolts 23 normally lie in the relative positions shown in Figure 3, and accordingly they do not interfere with the rotary movement of the valve device to closed position. 15 The cover 45, with its elastic bands 46 serves not only to uniformly distribute the paint peripherally with respect to the roller but also excludes air from the interior thereof. The device is particularly adapted for marking traffic lines on highways. 20 ways, as will be apparent.

The operation of the form of the device shown in Figure 4 is identical with that previously described, the only difference lying in the provision of means for positively supplying paint to the 25 roller, thus permitting the device to be used in any position. The pressure supply means shown in Figure 4, of course, is unnecessary in painting traffic lines on highways since the device is used in such a position that there is a free gravity flow 30 of paint to the roller at all times.

As soon as the use of the device has been completed, the rubber hose connections may be readily removed, whereupon the screws 28 may be removed to permit the roller to be detached from 35 the arm 19. The cover 45 is then readily removable by stretching one of the bands 46 over the roller, whereupon all of the parts of the device may be cleaned by using a suitable solvent according to the surface composition being employed. 40

The purpose of the plurality of studs 14 and nipples 15 is to permit rollers of different sizes to be employed. Where wider rollers are employed, such rollers may be supported from the 45 outer stud 14 by a suitable arm 19, and hose and piping connections similar to those illustrated may be connected to the outer nipple 15, as will be apparent. The plug 17 will be removed, of course, when the hose connection 32 is to be connected to the outer nipple 15, the plug 17, under such conditions, being secured into the inner 50 nipple 15.

The operation of the form of the invention 55 shown in Figures 5, 6 and 7 will be apparent from the foregoing description. The device is rolled over the surface to be treated in the same manner as the forms of the device previously described, and when the parts are connected in the manner shown in Figure 6, the surface coating composition will flow from the tube 53 to the pipe 65 and thence through the axial extension 67 into the interior of the roller. The paint is discharged from the roller through the openings 60 and is absorbed by the covering 75 to be uniformly 60 spread peripherally with respect to the roller to insure a uniform application of the paint. The openings 60 may be closed by operating the handle 63 to rotate the valve disk 61, each valve 62 closing one set of openings 60.

Instead of connecting the pipes as shown in Figure 6, the pipe 65 may be threaded on either of the tubes 54, thus adapting the device for applying paint on inclined surfaces. If the pipe 75 65 is connected to one of the tubes 54, the cap 55

from the latter tube is threaded on the tube 53 to form a closure therefor.

From the foregoing it will be apparent that either form of the device forms simple and effective means for applying paint and other surface 5 coating compositions wherever desired, and the device is particularly adapted for use in painting traffic lines on highways. The fabric covering in each case takes the place of a brush and remains saturated with paint as long as the device 10 is in operation, thus insuring the uniform application of paint where desired.

It is to be understood that the forms of the invention herewith shown and described are to be taken as preferred examples of the same and 15 that various changes in the shape, size and arrangement of parts may be resorted to without departing from the spirit of the invention or the scope of the subjoined claims.

I claim:

1. A device of the character described comprising a roller having peripheral openings, means for supplying a liquid surface coating composition to the interior of said roller, a valve device within said roller having portions movable across said 25 openings, said roller being provided with a slot, an operating handle projecting through said slot and connected to said valve device, and an absorbent applicator covering said openings.

2. A device of the character described comprising a roller having peripheral openings, means for supplying a liquid surface coating composition to the interior of said roller, a valve device within said roller having portions movable across said openings, said roller being provided 30 with a slot, an operating handle projecting through said slot and connected to said valve device, an absorbent applicator peripherally surrounding said roller and covering said openings, and resilient means for securing said applicator on said roller.

3. A device of the character described comprising a roller having peripheral openings, means for supplying a liquid surface coating composition to the interior of said roller, a valve device arranged in said roller and supported for rotation coaxially with respect thereto, said valve device having portions movable across said openings, said roller being provided with an arcuate 45 slot concentric therewith, an operating handle projecting through said slot and connected to said valve device, and an absorbent applicator surrounding said roller and covering said openings.

4. A device of the character described comprising a tank, an arm connected at one end to said tank and having bearing means at its other end, a surface coating applying roller having one side supported solely by said bearing means, and 60 means for supplying liquid surface coating composition from said tank to the opposite side of said roller axially with respect thereto.

5. A device of the character described comprising a hollow surface coating applying roller, 65 a tank, an arm connected to said tank, said arm being rotatably connected to one side of said roller and forming the sole support therefor, means for supplying liquid surface coating composition from said tank to the interior of said 70 roller axially with respect thereto, said roller being provided with peripheral openings, and an absorbent applicator surrounding said roller and covering said openings.

6. A device of the character described com- 75

prising a hollow surface coating applying roller, a tank, an arm connected to said tank, said arm being rotatably connected to one side of said roller and forming the sole support therefor, means for supplying liquid surface coating composition from said tank to the interior of said roller axially with respect thereto, said roller being provided with peripheral openings, an absorbent applicator surrounding said roller and covering said openings, and valve means within said roller for governing said openings.

7. A device of the character described comprising a tank, an arm connected at one end to said tank and having bearing means at its other end, a surface coating applying roller having one side supported solely by said bearing means, means for supplying liquid surface coating composition from said tank to the opposite side of said roller axially with respect thereto, said roller being provided with peripheral openings, and an absorbent applicator surrounding said roller and covering said openings.

8. A device of the character described comprising a tank, an arm connected at one end to said tank and having bearing means at its other end, a surface coating applying roller having one side supported solely by said bearing means, means for supplying liquid surface coating composition from said tank to the opposite side of said roller axially with respect thereto, said roller

being provided with peripheral openings, an absorbent applicator surrounding said roller and covering said openings, and valve means within said roller for controlling said openings.

9. A device of the character described comprising a tank, a single hollow arm rigidly secured at one end to said tank and communicating therewith, and a paint applying roller rotatably supported by the other end of said arm and communicating therewith.

10. A device of the character described comprising a tank, a single hollow arm rigidly secured at one end to said tank and communicating therewith, a paint applying roller rotatably supported by the other end of said arm and communicating therewith, said roller being provided with openings, and an absorbent applicator surrounding said roller and covering said openings.

11. A device of the character described comprising a tank, a single hollow arm rigidly secured at one end to said tank and communicating therewith, a paint applying roller rotatably supported by the other end of said arm and communicating therewith, said roller being provided with openings, an absorbent applicator surrounding said roller and covering said openings, and valve means within said roller for controlling said openings.

ALVA L. KITSELMAN, II.
